ROTARY PUMP

Harold E. De Ment, Decatur, and Herschel L. Wisnasky, Forsyth, Ill., assignors to Tryco Manufacturing Co., Inc., Decatur, Ill., a corporation of Illinois

Application September 22, 1951, Serial No. 247,786

1 Claim. (Cl. 103—135)

1 Our invention has to do with rotary pumps; an object being to provide a pump of simple and sturdy, as well as efficient design and construction such as will be a minimum of bother to operate and will be dependable to do the work set aside for it in a most satisfactory manner.

A further purpose of our pump is to provide a rotary pump, a resilient spring member, operable with the sliding blades of the pump and a centering pocket below it, for seating a dip in the spring body center to automatically urge a centering action constantly on the position of the spring, thus preventing it from sliding to one side and rubbing against the cylinder side walls.

A further purpose of our new rotary pump is to provide in such a pump the combination of centering means giving the spring longer wear with a true pump cylinder having a blade mounting that is eccentric axially and with the blades slidable radially as their eccentric supporting axis is rotated where it extends through such a cylinder.

A particular purpose of our new rotary pump is to provide in one simple and sturdy assembly a combination of pump housing, the end walls of which are shaped to define blade supporting spindle bearings registering in an eccentric position in the cylinder of the housing with the pump blades operatively slidable radially in and out from the axis and with it, a centering spring under each blade and with an intake and outlet port defined in spaced position from each other about the arcuate wall of such cylinder.

We achieve the purposes of our new pump by the invention disclosed in this specification, defined in the claim and shown in the drawings, wherein:

Fig. 1 is a section detail in perspective of our new rotary pump.

Fig. 2 is an end view of our invention with end plate removed.

Fig. 3 is a side view of the blade centering spring in our pump.

Fig. 4 is an end view of our pump.

Fig. 5 is a detail of blade spring fitting position in this pump.

We shall now set forth our disclosure of this invention as we refer to the drawings occasionally to make its functions and construction the more fully comprehensive.

We are aware of the existence of certain other forms of rotary pumps, but our new pump is constructed to provide new and novel features of operative improvement over others that may have some detail of remote similarity in design.

2

In fact we feel that the serviceable details of our pump construction will define means for a more sturdy operative assembly and will do more work with less upkeep effort than any such pump of similar general appearance.

Thus for a more detailed analysis of our new rotary pump we first wish to point out the housing 1 of our pump which has a central cylinder 2, a pair of opposed end plates 3 and 4 closing cylinder 2 and each provided with an eccentric bearing hole 5 and 6 respectively for the rotary support of shaft 7 which in turn has an integral pump-blade mounting 8 provided with a series of radially disposed slots 9 for the operative slidable support of pump blades 10 therein.

A novel design and construction of spring 11 (see Fig. 5) operable to set up as shown in each of center pockets 21 under the respective blades 10, is adapted to hold the spring 11 centrally and away from the inner cylinder end walls 12 of the pump.

Note that bottom coils 22 and 23 and top coils 24 and 25 of spring 11 are thus formed to give this spring 11 longer wear in its operative position in its slots 9. Note too that spring 11 is held centered by its center body dip 26 as it seats into center pocket 21.

Note too, that since shaft 7 is operable to rotate in an off center position where it extends through cylinder 2 with its slots 9 in blade mounting 8, then this very action causes blades 10 to slide in and out in slots 9 as they whirl with centrifugal force, out against inner wall 12 of cylinder 2 with spring member 11 constantly and resiliently urging blades 10 to press outwardly in their central position where they thus effect a most forceful pumping action as they swing through the widening crescent area 13 of the pump cylinder 2.

The central blade mounting 8 has all of its blade slots 9 (which slidably house blades 10), disposed in an angular position (see these slots in Fig. 2).

Thus by this angular position of slots 9 the position of contact of blades 10 with inner wall 12 of cylinder 2 tends to urge just enough binding stress of blades 10 to create a more firm and a more effective rotary pumping force; while this construction in combination with the operative efficiency of spring 11 behind each blade 10 defines a new and most novel and effective rotary pump construction.

Note too, that when liquids are moved by whirling blades 10 these liquids are picked up at port 14 at the thin end 15 of crescent space 13 and discharged under great pressure at the opposed

port 16 at opposed thin end 17 of crescent area 13.

It will be seen that intake port 14 communicates with crescent area 13 through intake slot 18; while outlet port 19 communicates with crescent area 13 through outlet slot 20.

Having thus set forth the outstanding features of operative efficiency of our new rotary pump, what we claim is:

A rotary pump comprising a housing shaped to define a horizontal central cylinder, a shaft 10 bearing axially eccentric at each end thereof, and a pumping blade supporting shaft operable to rotate eccentrically in said bearings to produce a pumping action, a rotary blade support housing, fixed on said shaft and provided with blade slots 15 disposed in angular position with said shaft, pump blades slidably housed in said angular slots, each respectively, for an outward urge by centrifugal force when said pump is running and a spring housed under said blades each respec- 20

tively, said spring provided with a central body dip and the bottom center of each of said angular slots pocketed, to hold said spring dip in center, and an intake and opposed outlet pipe connection with said housing, said spring provided with bottom terminal coils and outwardly urging cross fingers each also provided with terminal coils to make the spring longer lasting for wear.
